UNITED STATES PATENT OFFICE

2,459,381

TRUSS

Fred Hollingsworth, Grand Rapids, Mich., assignor to Doctors Truss Company, Grand Rapids, Mich., a corporation of Michigan

Application October 30, 1946, Serial No. 706,767

4 Claims. (Cl. 128—95)

1

This invention relates to improvements in trusses.

The main objects of this invention are:

First, to provide a truss comprising a body portion molded integrally of yieldable natural or synthetic rubber and having pads formed integrally therewith.

Second, to provide a truss comprising a pair of resilient pads forming part of a resilient body, the body being reinforced, the reinforcement carrying attaching means for the supporting belt and positioning straps.

Third, to provide a truss which is highly efficient in supporting the rupture or ruptures, and which may be effectively anchored or secured in position.

Fourth, to provide a truss comprising an integral molded body and pads which, while embracing a substantial area of the body, is effectively ventilated.

Further objects relating to economies and details of the invention will appear from the description to follow. The invention is defined in the claims.

A structure which embodies the features of the invention is illustrated in the accompanying drawing, in which:

Fig. 1 is a front or outer side elevational view of a truss embodying my invention, fragments of the supporting straps and belt being illustrated.

Fig. 2 is an enlarged vertical section on a line corresponding to line 2—2 of Fig. 1.

Fig. 3 is a fragmentary inner side view of the truss body, parts being broken away to show structural details.

Fig. 4 is an enlarged fragmentary view in section on line 4—4 of Fig. 1.

In the accompanying drawing 1 represents the belt or body strap and 2, 2 the leg straps which are slidably secured by the loops 3 to the body belt. The body member of my truss comprises top, bottom, and intermediate horizontal members 4, 5, and 6 respectively. These members are integrally joined at their ends by the downwardly converging end members 7 molded integrally with the horizontal members and having elongated downwardly converging pads 8 on their inner sides. The rear sides of the end members are provided with elongated recesses 9.

The bottom horizontal member 5 has an upwardly curved under side or wall 10 providing an arch or recess. The vertical connecting members 11 and 12 connect the horizontal members so that they are not distorted even when under considerable stress.

2

The reinforcing member 13 is in the form of a flat blade or strip of material, preferably spring steel, and its ends terminate in bosses 14 on the inner edges of the recesses 9. This reinforcing member has threaded holes 15 in its ends, into which the headed studs 16 are threaded. The lower ends of the end members are provided with slot-like holes 17 through which the front ends of the straps 2 are arranged, these straps terminating in coupling members 18 having key-hole slots 19 therein engageable with the studs.

The body belt 1 is provided with terminal couplings 20 corresponding to the couplings 18 and having key-hole slots therein engageable with the studs. The belt is commonly adjustable, but that is not illustrated.

With the parts thus arranged, the pads are supported in proper position for a double hernia although the truss may be used for single hernia, the second pad being effective as an anchoring element, that is, to keep the truss from shifting on the body of the wearer, and to equalize and distribute stress.

It will be understood that the truss may be made in various sizes, although one size pad is adapted for a considerable range of conditions.

I have illustrated and described my invention in an embodiment thereof which I have found highly desirable. Natural rubber of the desired resilience and flexibility may be used, although certain synthetic rubbers are desirable on account of the slow deterioration factor resulting from contact with the body. The body of the truss may be quite flexible so that it conforms readily to the wearer. The stresses are effectively sustained by the reinforcing member 13, so that even though the truss is quite resilient it is not distorted when subjected to stresses due to body movement. I have not attempted to illustrate or describe further adaptions which I contemplate, as it is believed that this disclosure will enable those skilled in the art to adapt or embody the invention as may be desired.

Having thus described my invention, what I claim as new and desire to secure by Letters Patent is:

1. In a truss, a body member of molded yieldable material comprising vertically spaced top, bottom, and intermediate horizontal members, and downwardly converging end members integral therewith, the end members substantially exceeding the horizontal members in width, and having downwardly converging elongated pads on their inner sides molded integrally therewith and elongated recesses on their outer sides, the

horizontal members being integrally connected centrally thereof, a springable blade-like reinforcing member imbedded in the intermediate horizontal member with its ends at the inner edges of said recesses, and attaching studs engaged with the ends of said reinforcing member and projecting to the outside of said body member and adapted to be connected to supporting straps for said truss.

2. In a truss, a body member of molded yieldable material comprising vertically spaced top, bottom, and intermediate horizontal members, and downwardly converging end members integral therewith and having downwardly converging elongated pads on their inner sides molded integrally therewith and elongated recesses on their outer sides, a springable blade-like reinforcing member imbedded in the intermediate horizontal member with its ends at the inner edges of said recesses, and attaching studs engaged with the ends of said reinforcing member.

3. A truss comprising a body of molded yieldable material and consisting of vertically spaced top, bottom, and intermediate horizontal members and downwardly converging end members integral therewith and having elongated downwardly converging pads on their inner sides, the end members having elongated recesses in their outer sides, the under side of the horizontal member being upwardly arched, the horizontal members being centrally connected, there being a flat, springable reinforcing member imbedded in said intermediate horizontal member, and outwardly projecting studs engaged with the ends of said reinforcing member and adapted to receive at-

taching straps, the studs being positioned at the inner edges of the pads and centrally thereof, the end members having strap-receiving holes through the lower ends thereof opening to said recesses, the pads extending inwardly beyond the inner sides of said horizontal members so that the inwardly directed stress of the straps is sustained by the pads.

4. A truss comprising a body of yieldable material and consisting of vertically spaced top, bottom, and intermediate horizontal members and downwardly converging end members integral therewith and having elongated downwardly converging pads on their inner sides, there being a reinforcing member imbedded in said intermediate horizontal member, and outwardly projecting studs engaged with the ends of said reinforcing member and adapted to receive attaching straps, the studs being positioned at the inner edges of the pads and centrally thereof, the pads extending inwardly beyond the inner sides of the said horizontal members so that the pads sustain the inward thrust of the straps when the truss is in use.
